(57) CLAIM

The ornamental design for a round ball bed leg cover, as shown and described.

DESCRIPTION

FIG. 1 is a front perspective view of a round ball bed leg cover showing my new design;

FIG. 2 is a rear perspective thereof;

FIG. 3 is a top plan view thereof;

FIG. 4 is a bottom plan view thereof;

FIG. 5 is a rear elevation view thereof; and,

FIG. 6 is a front elevation view thereof.

The dot-dash broken lines define the bounds of the claimed design and form no part thereof.
